Primary Examiner — Mary Ann Calabrese(74) Attorney, Agent, or Firm — Mohr Intellectual Property Law Solutions, PC(57) CLAIM

I claim the ornamental design for mobile workstation, as shown and described.

DESCRIPTION

FIG. 1 is a perspective view of a mobile workstation.

FIG. 2 is a front elevation view thereof.

FIG. 3 is a rear elevation view thereof.

FIG. 4 is a top plan view thereof.

FIG. 5 is a bottom plan view thereof; and,

FIG. 6 is a right-side elevation view thereof, the left-side elevation view being a mirror image of the right-side elevation view.
